[57] ABSTRACT

A yoke assembly having windings for producing mag-

netic fields to deflect an electron beam in a predetermined manner. A first and a second set of windings are disposed upon a core for deflecting the electron beam in a vertical and a horizontal sense, respectively. A set of four auxiliary windings is disposed upon the core about points where the horizontal and vertical deflection windings would ordinarily overlap. The auxiliary windings are then connected in series to form a closed, four-sided loop or bridge. The bridge is connected in series with both the first and the second set of deflection windings such that the windings of the first set are coupled to opposing nodes of the bridge, and the windings of the second set are coupled to the other, remaining nodes. The effective resistances across the newly-connected first and second sets of windings are substantially decreased while the inductances thereof are virtually unchanged so that the L-R ratios thereof are substantially improved.

In one embodiment, the first and second sets of windings are distributed in patterns characterized by relatively low fifth-order and higher harmonics. In still another embodiment, each auxiliary windings has turns of an additional adjacent auxiliary winding interposed intermediate its ends.

DEFLECTION YOKE WITH BRIDGE-CONNECTED WINDINGS

BACKGROUND OF THE INVENTION

The present invention relates to electromagnetic devices and, more particularly to improved electromagnetic means for deflecting electron beams in a cathode ray tube.

In order to produce a display upon the face of a cathode ray tube, it is necessary to provide means for deflecting an electron beam, or beams, across the face of the tube in a predetermined manner. Various means may be selected to provide this function and both electrostatic and electromagnetic means have been successfully utilized for effecting repeated beam deflection. In cathode ray tube systems utilized for television receivers, however, electromagnetic means are predominantly used.

A continuing problem which has faced designers of television receiver deflection systems has been the non-linearity of the sawtooth-like waveform which arises in horizontal deflection windings by virtue of the integration of square-wave voltages applied thereto. While a perfect inductor would produce a linear rise in current, the resistance inherent in actual inductive devices detracts from the operation of the deflection windings and causes the current rise to be non-linear.

An improved inductance-to-resistance, or L-R, ratio increases the efficiency of deflection windings through reduced I^2R losses, which results in a substantially cooler-operating device. The sensitivity of the device is also increased, resulting in better system performance. It will be appreciated that even when utilizing compensating means in circuit with the deflection windings, the inherent L-R ratio of the deflection yoke remains substantially unaffected. It will therefore be appreciated that it would be desirable to provide improved deflection means having better linearity characteristics and a superior L-R ratio than those previously known.

It is therefore an object of the present invention to provide improved deflection means for a television receiver.

It is a further object to provide a deflection yoke assembly having an improved L-R ratio.

It is another object to provide an improved deflection winding utilizing bridge-connected coils.

It is still another object to provide a toroidal deflection winding having an improved L-R ratio and which is readily manufactured.

SUMMARY OF THE INVENTION

Briefly stated, in accordance with one aspect of the invention, the foregoing objects are achieved by providing a set of four auxiliary windings upon a core assembly in conjunction with a first pair of windings which provide vertical deflection, and a second pair of windings which effect horizontal deflection, of an electron beam. Each of the four auxiliary windings is a "hybrid" winding constituted by turns which correspond to what would otherwise be adjacent or overlapping turns of juxtaposed horizontal and vertical deflection windings. Each of the four auxiliary windings is disposed about a point on a yoke between a horizontal and a vertical winding. The four auxiliary windings are then connected in series to form a closed, four-sided loop which resembles a bridge. Each of the vertical deflection

windings is connected to an opposite corner of the bridge. Each of the horizontal deflection windings is then coupled to one of the remaining, opposite corners or nodes of the bridge. Currents flowing through both the horizontal and the vertical deflection windings thus traverse all four of the bridge-connected windings, resulting in either additive or differential currents therein. The bridge-connected windings interposed in the deflection circuits may serve to maintain the effective inductances thereof, while lowering the series resistance of each circuit so that the L-R ratios are markedly improved. Alternatively, smaller wire may be used for the bridge windings. The increased resistance of the bridge windings may thus maintain the original L-R ratio, while affording a substantial saving in conductor material.

In another embodiment, a yoke winding is disclosed which utilizes bridge-wound turns in combination with vertical and horizontal windings which overlap certain of the bridge windings. The distribution of the vertical and horizontal windings provides desirable beam deflection characteristics while facilitating the disposition of turns on the core in a continuous, progressive manner.

In still another embodiment, ones of the turns of each bridge winding are interchanged with corresponding turns of an adjacent bridge winding. The interchanged turns produce additive magnetic flux for deflection current flowing in a first direction, and bucking magnetic flux for deflection current flowing in the opposite direction.

BRIEF DESCRIPTION OF THE DRAWINGS

While the specification concludes with claims particularly pointing out and distinctly claiming the subject matter which is regarded as the invention, it is believed that the invention will be better understood from the following description of the preferred embodiments taken in conjunction with the accompanying drawings in which:

FIG. 1 is a schematic drawing of a set of horizontal and vertical deflection windings as utilized in the prior art;

FIG. 2 is a sectional view of a toroidal coil and core assembly showing the disposition of various windings upon the core in accordance with the teachings of the prior art;

FIG. 3 is a schematic drawing of an improved deflection winding circuit constituting one embodiment of the present invention;

FIG. 4 is a cross-sectional diagram showing a developed quadrant of a toroidal yoke core having windings distributed therein;

FIG. 5 is a plot of the distribution of the effective horizontal deflection winding of FIG. 4;

FIG. 6 is a plot of the distribution of the effective vertical deflection winding of FIG. 4;

FIG. 7 is a cross-sectional diagram showing another turns placement scheme on a developed quadrant of a toroidal deflection yoke;

FIG. 7a represents a portion of the developed quadrant of FIG. 7 showing a modified turn placement arrangement;

FIG. 8 is a plot of the distribution of the effective horizontal deflection windings of FIG. 7 and 7a;

FIG. 9 is a plot of the distribution of the effective vertical deflection windings of FIG. 7 and 7a; and

FIG. 10 is a schematic diagram showing a modified bridge-connected deflection circuit.

DESCRIPTION OF THE PREFERRED EMBODIMENTS

FIG. 1 shows, in simplified schematic form, a set of windings suitable for deflecting the electron beam of a cathode ray tube over the viewing screen or face thereof. A pair of vertical windings V_1 and V_2 are connected in series and coupled across a source of signals (not shown) which apply a periodic ramp-like or "sawtooth" current I_v to the windings. As will be understood by those skilled in the art, windings V_1 and V_2 are commonly disposed upon a magnetic core located adjacent the neck of a cathode ray tube. Magnetic flux produced by current flowing through vertical windings V_1 and V_2 is ordinarily oriented in a horizontal fashion in order to impart a vertical deflection to an electron beam passing therethrough. Similarly, horizontal windings H_1 and H_2 are connected across another source of periodic signals (not shown) for causing a sawtooth current I_h to flow therethrough. Horizontal windings H_1 and H_2 may advantageously be disposed upon a common core with vertical windings V_1 and V_2 , and displaced 90° therefrom in order to produce a vertical field for effecting the deflection of an electron beam in a substantially horizontal plane. The junctions of the pairs of horizontal and vertical windings may advantageously be connected together. Current is applied to the horizontal windings by means of a balanced source, such as the secondary winding of a transformer across which the windings are coupled. Horizontal windings H_1 and H_2 are thus allowed to "float" with respect to ground.

Referring now to FIG. 2, there is shown a simplified cross section of a toroidal core 10 upon which vertical and horizontal deflection windings are disposed in a manner commonly practiced in the prior art. Vertical windings V_1 and V_2 are placed diametrically opposite one another on the upper and lower halves of core 10, respectively. Similarly, horizontal windings H_1 and H_2 are disposed diametrically opposite one another upon the core and displaced substantially 90° from the vertical windings. In FIG. 2, as often occurs in the design of such devices, it will be seen that in order to provide the number of vertical winding turns necessary for proper deflection of an electron beam it has been necessary to extend the turns of horizontal windings H_1 and H_2 so as to overlap portions of vertical windings V_1 and V_2 . While in the idealized embodiment shown in FIG. 2 the overlapping produces two tiers of windings at various points about the core, in other instances desired magnetic characteristics may be achieved by interleaving turns of the windings in a single tier so as to extend the effective lengths thereof without producing a second, overlapping tier of windings. In either case, however, the magnetic flux enclosed by any two overlapping or adjacent turns of different windings is nearly identical.

It has been found that the overlapping or adjacent turns referred to may be treated as unitary winding elements rather than as separate but commingled horizontal and vertical winding turns. The overlapping or adjacent turns can therefore be electrically isolated and connected together so as to form a new, separate winding. In FIG. 2, the interleaved or overlapping turns of windings V_1 and H_2 are denominated W_a while the interleaved or overlapping turns of windings V_2 and H_2

are denominated W_b . Similarly, interleaved or overlapping turns of windings V_2 and H_1 are denominated W_c and those of windings V_1 and H_1 denominated W_d . If the sets of turns denominated W_a , W_b , W_c and W_d are removed from the core and replaced with four auxiliary windings formed from a continuous length of conductor, a set of four series-connected windings result. After joining opposite ends of the conductor, the four windings may be considered to be in a bridge configuration.

Turning now to FIG. 3, a schematic drawing of the newly-achieved winding system is shown. The four new, auxiliary windings are series-connected to form a closed loop and depicted as lying in a substantially square configuration in the manner of a bridge. The now-shortened deflection windings serve to connect the bridge windings across suitable sources of horizontal and vertical deflection currents. One end of the now-shortened vertical deflection winding denominated V_1' is coupled to one corner or node of the bridge at an intersection of two of the four new, auxiliary windings. Similarly, one end of the other attenuated vertical winding V_2' is connected to a node at the opposite side of the bridge, at the intersection of the other two of the four new windings.

Each of the shortened horizontal deflection windings H_1' and H_2' is connected to one of the remaining nodes of the bridge. The bridge-connected auxiliary winding whose ends are coupled to vertical winding V_1' and horizontal winding H_1' is denominated B_{11} , while that winding coupled between vertical winding V_1' and horizontal winding H_2' is denominated B_{12} . In like manner, the bridge winding lying between windings V_2' and H_1' is denoted B_{21} and that between windings V_2' and H_2' denoted B_{22} . All of the bridge-connected windings are thus in series circuit relationship with the vertical and the horizontal deflection windings. Both the horizontal and the vertical deflection winding circuits thus have placed in series therewith two parallel sets of windings, each set consisting of a pair of series-connected windings.

If in the original yoke windings:

X = the number of turns in each original horizontal winding H_1 and H_2 , and

Y = the number of turns in each original vertical winding V_1 and V_2 , then

$2X$ = the total number of horizontal turns connected in series and

$2Y$ = the total number of vertical turns connected in series.

Now, if N = the number of turns at the end of each winding which are adjacent to or overlap turns of an adjacent winding, after the deletion of these turns it will be understood that the yoke now will have

$X-2N$ turns per new horizontal winding H_1' and H_2' ; and

$Y-2N$ turns per new vertical winding V_1' and V_2' .

At each point where overlapping or adjacent turns of different windings have been removed, a new continuous winding having $2N$ turns is formed. Since at this location N turns have been deleted from each of the original windings the $2N$ turns of the new winding merely replace those deflection winding turns that have been eliminated.

A total of four of the new or auxiliary windings are formed, and are connected in a closed loop or bridge. Now, by coupling opposite junctions or nodes formed

between the bridge-connected windings in series with horizontal windings H_1' and H_2' a new circuit element composed of $4N$ turns connected in parallel with $4N$ turns is interposed in the horizontal deflection circuit.

If a constant R is taken to be the resistive multiplying factor in ohms per turn of winding material, it will be seen that the original horizontal deflection windings had a resistance R_h of $2RX$, while the original vertical windings had a resistance R_v of $2RY$. The inventive winding circuit, now including the bridge-connected windings, will present both the resistance of the shortened deflection windings and the resistance arising across the bridge windings to the deflection current supply systems so that the total resistance R_h' arising across the new horizontal deflection circuit is now

$$R[X-2N+(1/4N + 1/4N) + X-2N] \\ = R(X-2N+2N+X-2N)$$

or

$$2R(X-N)$$

so that the resistance of the new horizontal deflection circuit is reduced by $2RN$. Further, since the bridge-connected windings are now interposed between the shortened vertical deflection windings V_1' and V_2' , it will be seen that the effective series resistance R_v' of the vertical deflection circuit is now

$$R[Y-2N+(1/4N + 1/4N) + Y-2N] \\ = R(Y-2N+2N+Y-2N)$$

or

$$2R(Y-N)$$

so that the total resistance of the vertical deflection circuit has also been reduced by $2RN$.

While the resistance across both the vertical and the horizontal deflection circuits has been reduced, the magnetomotive force (mmf) of both circuits remains the same. Since magnetomotive force F is directly proportional to the ampere-turns of a winding it may be considered that the mmf of the horizontal deflection circuit F_h is equal to the current I_h through the circuit times the number of turns, or

$$F_h = 2I_h X$$

for the original horizontal circuit.

Each of the horizontal windings of the inventive circuit has had $2N$ turns removed therefrom, and with the bridge windings connected between the shortened horizontal windings H_1' and H_2' there are two paralleled windings of $4N$ turns each added to the horizontal circuit. Assuming that horizontal deflection current I_h divides equally between both parallel branches of the bridge-connected windings, recombining at the opposite side of the bridge and flowing outwardly through the distal horizontal deflection winding, the mmf F_h' of the horizontal deflection circuit when connected as shown in FIG. 3 may be represented as

$$I_h(X-2N) + I_h/2(4N) + I_h/2(4N) + I_h(X-2N) \\ = I_h(X-2N+2N+2N+X-2N)$$

or

$$2I_h X$$

so that the mmf and therefore the inductance of the new horizontal circuit including the bridge-connected windings is substantially the same as that of the original deflection windings alone. Moreover, the spatial distribution of the mmf giving rise to the magnetic flux about the windings is substantially the same. It may easily be demonstrated that the above relationship also holds true for the new vertical deflection circuit shown in FIG. 3 so that the magnetic and inductive characteris-

tics of the vertical deflection system are also unchanged. From the standpoint of the magnetic characteristics of the deflection system the total number of effective turns in the inventive horizontal deflection circuit is still $2X$, and the total number of effective turns in the vertical circuit is still $2Y$. Hence, the total inductance of both the horizontal and the vertical deflection circuits has not been changed. It can now be appreciated that, using the same amount of conductor material as was utilized for a prior-art style yoke winding, the L-R ratio of the horizontal deflection circuit has been increased by $100(N/X-N)$ per cent and the L-R ratio for the vertical deflection circuit has been increased by $100(N/Y-N)$ per cent.

The various bridge-connected auxiliary windings conduct differential currents whose characteristics depend upon the relative phase and magnitudes of vertical and horizontal deflection currents I_v and I_h . Assuming current flow in the directions indicated in FIG. 3, it will be seen that currents I_h and I_v are additive in windings B_{12} and B_{21} and subtractive in windings B_{11} and B_{22} . The change in ampere-turns thus achieved corresponds to the decrease in magnetic flux which would result from opposing current flows in the interspersed turns W_a and W_c which the windings B_{11} and B_{22} replace. Similarly, the increase in ampere-turns due to the additive currents through windings B_{12} and B_{21} corresponds to the increased flux which would result from the application of the individual deflection currents to the separate, interspersed horizontal and vertical turns W_b and W_d at corresponding locations upon the yoke.

Damping means comprising capacitor 12 and resistor 13 are connected in series between the input terminals of vertical winding V_1' and horizontal winding H_2' . Similarly, the series combination of a capacitor 14 and resistor 15 are connected between the output terminals of vertical winding V_2' and horizontal winding H_1' . The damping means serve to minimize ringing or oscillation which may be induced in the vertical deflection windings due to the presence of higher-frequency signals in the horizontal deflection windings. Of course, other circuitry may be adapted for the purpose and it will be appreciated that the series R-C circuits are shown for purposes of illustration, the bridge winding arrangement shown being amenable to various other damping arrangements as required.

Alternatively, rather than increasing the L-R ratios of the respective deflection circuits the size of the conductor used for the bridge-connected windings may be reduced. A reduction in cross-sectional area of the conductor effects a corresponding increase in the resistance thereof, lowering the L-R ratio but saving conductor material. For instance, if the $2N$ turns of wire per bridge winding are constructed of wire having one-half the cross-sectional area of the wire used for windings V_1' , V_2' , H_1' , and H_2' , the inductance of the resulting deflection circuits will be substantially the same as that of the original circuits; but since the resistivity of the bridge circuit is doubled the overall series resistance of the horizontal and vertical deflection circuits will match that of the original, prior-art yoke winding configuration.

It will therefore be seen that it is advantageous to use as many bridge-connected turns as possible in a given deflection system configuration. In the ultimate it may be desirable to use only bridge-connected windings, re-

ducing the number of peculiarly horizontal and vertical winding turns to zero. In general, however, the required winding distributions militate against this approach.

One winding distribution which is considered optimal for a toroidal yoke used in conjunction with color television receiver cathode ray tubes in which three electron beams disposed in a planar array are deflected over a maximum included angle of 70° is shown in FIG. 4. This embodiment incorporates an economic advantage in that it may be constructed by continuous winding of conductor material about the core, while including an interleaving and overlapping of windings which provides the desired winding distribution.

FIG. 4 shows a composite winding distribution upon the developed surface of one quadrant of an annular core, which includes one half of horizontal winding H_1' , bridge winding B_{21} , and one half of vertical winding V_1' . It is assumed that the turns are deposited on the core by winding from right to left, the start of each winding being denoted by S and the finish or final turn by F.

The winding distributions on adjacent yoke quadrants being symmetrical, it will be understood that the major part of winding H_1' is disposed in a continuous fashion for approximately 22 slots on either side of a point denominated 0° on the yoke core with a small, discontinuous group of turns displaced substantially four slots from either end thereof. Similarly, the bridge-connected auxiliary windings B_{21} and B_{22} are oriented symmetrically about the 0° position and extend in a continuous manner on either side thereof for 35 slots, resuming after a hiatus of four slots and extending again for substantially 12 slots.

The vertical deflection windings V_1' and V_2' are disposed about the 90° and 270° positions upon the core, respectively. They are distributed outwardly therefrom and so bracket the 0° position in a symmetrical fashion. FIG. 4 shows the right-hand half of vertical winding V_1' , it being considered unnecessary to illustrate the entire winding due to its symmetrical nature. The turns extend in a continuous fashion for approximately 14 slots about the 90° position, and then in three separate sets of eight, five, and four turns spaced outwardly from the ends of the central winding segment by substantially five, 15, and 26 slots respectively.

It is evident that while the bridge-connected windings are disposed in both a first and a second tier, the bridge windings actually occupy only a single layer at any point upon the core surface. Similarly, both the vertical and the horizontal windings comprise single layers, each remaining in a single tier. This winding configuration lends itself to ease of manufacture, since the various windings may be disposed upon a toroidal yoke by progressively winding in a common direction about the toroid, with no need of "backing up" to deposit a second layer of windings. Vertical windings V_1' and V_2' are deposited first, and then the various bridge windings are formed on the core. Finally, the horizontal windings H_1' and H_2' are disposed in a second tier over the bridge windings and the vertical deflection windings.

Of course, facility of disposition of the windings upon a core is secondary to the proper distribution of the deflection winding turns. As used herein, the term "winding distribution" indicates the overall magnetic effect produced by a group of inter-related turns, rather than the discrete positioning of the turns thereof. In calcu-

lating the effective winding distribution, bridge-connected winding turns are assigned a value one-half that of the turns within exclusively horizontal or vertical deflection windings. As explained above, it is considered that each bridge-connected winding conducts one-half of the horizontal deflection current and one-half of the vertical deflection current.

Referring now to FIG. 5, the effective winding distribution in the overall horizontal circuit of FIG. 4, including the bridge-connected windings appended thereto, is shown. The vertical axis represents the percentage of the total turns extending from the geometric center of the winding to the distal end thereof. The horizontal axis represents angular position on the yoke, it being recognized that the actual number of slots or turn positions varies with conductor size and the diameter of the core means. The distribution of FIG. 5 thus may be used to characterize physically different windings which have similar magnetomotive characteristics, regardless of the actual number of turns or the diameter of the core means.

Similarly, FIG. 6 represents the effective vertical deflection winding distribution from the geometric center to one extremity thereof, including bridge-connected winding B_{21} which lies in the illustrated yoke quadrant and contributes to the overall vertical winding distribution. As set forth above, the winding distribution shown, while illustrative of the actual turn placement set forth in FIG. 4, may be considered characteristic of the geometric winding type which produces the desired magnetic flux characteristic.

As will be recognized by those skilled in the art, a two-dimensional configuration such as a waveform, or a spatial distribution such as the turns placement shown in FIG. 4, may be considered to be constituted by an infinite series of sinusoidal functions whose frequencies are integral multiples of a fundamental frequency. Where the frequency multiplier is greater than one, the function is termed a harmonic. Such a series, known as a Fourier series, may be represented in a form

$$A \sin \phi + B \sin (3\phi) + C \sin (5\phi) + D \sin (7\phi) + E \sin (9\phi) + F \sin (11\phi) + G \sin (13\phi) + \dots$$

Due to the symmetry of the present winding distribution even-numbered harmonics, i.e. those having even-numbered frequency multipliers, are not present. A Fourier analysis of the overall horizontal deflection winding distribution of FIG. 4 including the bridge winding turns, which are assigned a value one-half that of horizontal winding turns, reveals that the coefficient of the third harmonic (B) is substantially greater than those of other, higher order harmonics. On a normalized scale wherein the coefficient A of the fundamental is taken as 1, the coefficients calculated for the instant winding distribution are

B	0.0818
C	0.0055
D	-0.0059
E	-0.0078
F	0.0034
G	-0.0061

so that harmonics of higher than the third order are relatively low. Analysis shows that the contribution made by fifth and higher-order terms is relatively insignificant, so that the winding distribution illustrated in FIG. 5 can be substantially reconstructed by combining a

normalized fundamental and the above third harmonic value.

The overall vertical deflection winding distribution, which reflects the effective value of the bridge windings, produces a Fourier series the coefficients of which have absolute values somewhat similar to those of the horizontal distribution. On a normalized scale, the coefficients calculated for the vertical winding distribution of FIG. 4 are

B	-0.0646
C	0.0001
D	-0.0050
E	0.0011
F	0.0027
G	0.0078

so that again, the third harmonic is much larger than higher-order harmonics. Here also, analysis has shown that the effective distribution illustrated in FIG. 6 may be substantially reproduced from the fundamental and the third harmonic.

The winding distribution thus characterized, in addition to facilitating the disposition of the various turns upon a core, produces magnetic fields well adapted for the deflection of electron beams in a color cathode ray tube of the type in which three electron beams are disposed in a planar array. It is contemplated that other, equivalent combinations of winding turn placements may be utilized to produce effective distribution shown.

A turns location arrangement utilizing bridge-connected windings which is presently preferred for a toroidal yoke used in conjunction with a color cathode ray tube of a type in which three electron beams disposed in a triangular or "delta" array are deflected over a maximum included angle of 90° is shown in FIG. 7. As was the case in FIG. 4, the symmetry of the toroidal winding allows the entire turns placement scheme to be characterized by one quadrant thereof. As before, the 0° position on the developed core corresponds to the midpoint of the right-hand side of the idealized yoke represented in FIG. 2. Horizontal deflection winding H_1' is thus centered about the 0° position, while vertical deflection winding V_1' is centered about the 90° point.

FIGS. 8 and 9 show the cumulative percentage of the total effective turns from the center of each winding to the distal end thereof, including the associated bridge-connected winding. The solid curve of FIG. 8 represents the cumulative number of effective turns, assigning each turn of a bridge-connected winding one-half the value of a turn of the peculiarly horizontal winding. The winding distribution shown in FIG. 8 therefore incorporates the effective turns of both one half of horizontal winding H_1' and the bridge-connected auxiliary winding B_{21} , it being realized that the same bridge winding also contributes to the vertical winding distribution. It will be understood that the effective horizontal turns actually extend for somewhat less than 180° upon the yoke, the dotted portions of the curve which extend illustrating the characteristics of a modified winding distribution to be discussed below.

As was the case for the winding distribution whose turns placement was illustrated in FIG. 4, the present horizontal winding distribution may be characterized by a Fourier series of the form

$A \sin \theta + B \sin (3\theta) + C \sin (5\theta) + D \sin (7\theta) + E \sin (9\theta) + F \sin (11\theta) + G \sin (13\theta) + \dots$ On a normalized scale, the coefficients calculated for the horizontal winding distribution of FIG. 7 are:

B	-0.0059
C	-0.0006
D	-0.0004
E	0.0028
F	-0.0064
G	0.0007

so that all of the harmonics are very small with respect to the fundamental. It can be demonstrated that the effective horizontal winding distribution of FIG. 8 can be substantially reconstructed utilizing only the fundamental, the equivalent of a substantially sinusoidal distribution.

FIG. 9 is a plot of a preferred vertical winding distribution. In FIG. 9, the vertical axis represents the percentage of the total number of effective turns from the center of the winding to the outer end thereof, while the horizontal axis corresponds to the developed length of a quadrant of the inner surface of an annular core upon which the windings are disposed. As explained with reference to FIG. 8, turns of bridge windings associated with the vertical windings of interest are each assigned one-half the value of an exclusively vertical winding turn, since the vertical deflection current which is carried by the bridge windings is one-half that carried by the vertical deflection winding itself. A Fourier analysis of the effective vertical winding distribution shows that, in contradistinction to the effective horizontal winding distribution of FIG. 5, the fifth harmonic coefficient (C) is not insignificant. The distribution represented in FIG. 9 may therefore be approximated by a Fourier series of the type indicated above wherein the normalized coefficients are

B	0.0397
C	0.0158
D	-0.0006
E	0.0093
F	-0.0131
G	-0.0027

While the set of Fourier coefficients listed above describes the winding distribution to a high degree of accuracy, it has been found that a winding distribution reconstructed from the fundamental, third and fifth order harmonics substantially duplicates the desired effective distribution. The described winding distribution has been found to have characteristics which are highly desirable for use in a toroidal yoke in conjunction with a color television cathode ray tube of the type wherein three electron beams disposed in a triangular or delta array are deflected through a maximum included angle of 90°.

Turning now to FIG. 10 there is shown still another form of bridge-connected winding, which produces different fluxes for similar horizontal and vertical currents applied thereto. As before, the various horizontal and vertical deflection windings are connected to opposing corners of other, auxiliary windings which in turn are connected in a bridge configuration. In FIG. 10, however, certain turns of each bridge winding have been interchanged with corresponding turns from an adjacent winding. Bridge winding B_{11} , for instance, comprises a first segment P and a second segment p while

bridge winding B_{21} , which also receives current from horizontal winding H_1' , comprises first and second segments Q and q respectively. Bridge winding B_{12} , which is connected to horizontal winding H_2' , comprises a first segment S and a second segment s while the other bridge winding B_{22} connected to horizontal winding H_2' comprises first and second segments T and t , respectively. For purposes of illustration, it will be assumed that all of the first segments of each bridge winding contain like numbers of turns, as do all of the second segments so that the turns comprising the second segments of each bridge winding may be interchanged with those of an adjacent bridge winding. The turns which comprise winding segment q are interchanged with those of segment p , and the turns of segment s are interchanged with those constituting segment t . By proper connection of the interchanged winding segments a circuit like that schematically represented in FIG. 10 is obtained.

The direction of vertical deflection current I_v is indicated by solid arrows, and the direction of horizontal deflection current I_h by dashed arrows. Assuming that the turns of all bridge-connected windings are wound about the core in a common direction, it follows that adjacent winding segments which carry like-directed current will produce like-directed magnetic flux. Similarly, winding segments in which currents flow in opposite directions produce oppositely-directed fluxes. For example, the vertical deflection current I_v in first winding segment P of bridge winding B_{11} is directed in a manner similar to that of second winding segment q which is adjacent thereto. However, horizontal deflection current I_h , whose direction is indicated by the dotted arrows, flows through the first winding segment P in a direction opposite to that through second winding segment q .

The magnetic flux supported by the various bridge windings is increased by additive currents in the first and second portions thereof, and decreased by subtractive or differential currents. In the present instance the vertical deflection characteristics, and therefore the effective vertical winding distribution, remain unchanged despite the altered bridge winding configuration. In contrast the horizontal winding distribution, and therefore the deflection characteristics resulting therefrom, is substantially modified. Each bridge-connected winding may now be considered to consist of a first winding segment derived from the original winding and a second winding segment borrowed from its neighbor. If there are $2n$ turns in each of the second winding segments p , q , s , and t and $2N$ turns in each original bridge-connected auxiliary windings so that the first winding segments each comprise $2(N-n)$ turns, the mmf produced by vertical current $I_v/2$ flowing in any bridge-connected winding will be $I_v N$ while the flux produced by horizontal current $I_h/2$ flowing therethrough will be $I_h(N-2n)$. The inductance presented to the vertical deflection system will thus remain unchanged, while the inductance presented to the horizontal deflection system will be reduced. The winding configuration shown in FIG. 10 thus provides a modified distribution for one of the deflection winding circuits at the expense of a somewhat lessened L-R ratio.

Referring now to FIG. 7a, there is shown a portion of the developed toroidal core quadrant represented in FIG. 7, with windings represented thereon in cross sec-

tion. FIG. 7a shows only the windings disposed at one side of the juncture of the two quadrants which form the upper half of a toroidal yoke of the type illustrated in FIG. 2, wherein the right-hand extremity is taken to be 0° and top dead center is 90° . The 90° position is located at the rightward end of the developed view shown in the Figure. In the distribution of FIG. 7, bridge winding B_{21} begins at slot 60 (approximately 82°) and is wound in a progressive clockwise fashion to slot 3 which is located at approximately 4° on the core, the initiation or starting point of the bridge winding being denominated SB_{21} and the end or finish FB_{21} . Vertical winding V_1' is disposed in a second tier over winding B_{21} for the first 42° of the bridge-connected winding. The vertical windings are disposed in the unoccupied first tier between the 82° and 90° points or between the initial turn of bridge winding B_{21} to the final turn of bridge winding B_{11} . In order to produce the necessary winding distribution, however, a single tier of vertical windings between 82° and 98° (slots 61 through 72) is inadequate. For this reason, seven additional vertical winding turns are disposed in a second tier in alternating positions. It will now be seen that there are a total of nine effective vertical turns lying in slots 67-72 of the second quadrant.

FIG. 7a shows in developed form the rightward end of the yoke quadrant shown in FIG. 7. In order to optimize the use of the bridge windings and increase the L-R ratio of the vertical windings, some of the vertical winding turns which had originally been disposed in slots 61-66 have been deleted and certain bridge-connected winding turns have been added. The turns placement and connection gives rise to an asymmetrical mmf contribution from the bridge windings to produce an effective winding distribution which is substantially identical to that of FIG. 7 for the vertical windings, and nearly so for the horizontal windings.

It will be recalled that the bridge windings as disclosed above necessarily carry both horizontal and vertical deflection current. Therefore, in providing bridge-connected winding turns of the type heretofore described it would be necessary to accept horizontal flux components over the length of the entire bridge-connected winding. It would in some cases be detrimental to the deflection characteristics desired, however, if such horizontal components were to appear in the area about the 90° point of the yoke.

The distribution of the turns of the bridge-connected windings shown in FIG. 7a provides the advantages which inhere in the bridge winding configuration to the vertical deflection circuit without introducing unwanted magnetic flux arising from the horizontal deflection signals. In FIG. 7a bridge winding B_{21} and B_{11} are each extended by a total of six turns to replace the first tier of vertical deflection windings lying in slots 61-66 and 67-72, respectively; and three vertical winding turns are added to the second winding tier. Since each bridge winding turn has only one half the effective value of a corresponding vertical winding turn, the six vertical turns and six bridge turns equal nine effective vertical turns, the same number as had originally been disposed in slots 60-66. Since the windings are symmetrically distributed about the 90° position, the effect is the same for turns of winding B_{11} in slots 67-72. The mere provision of bridge winding turns, however, will still support horizontal flux components, as set forth above.

To cancel the effect of horizontal current in certain bridge winding turns, the winding connection shown in FIG. 10 is utilized. The first turn of bridge winding B_{21} is placed in slot 72, the winding progressing in a clockwise fashion about the core, herein corresponding to a leftward direction. A total of three turns of bridge winding B_{21} are interchanged with three turns of adjacent bridge winding B_{11} . In the present illustration, turns of winding B_{21} lying in slots 61, 62, and 66 are removed, and the three turns thus eliminated are placed in slot 67, 71 and 72 and so are interspersed with turns of bridge winding B_{11} . The turns of bridge winding B_{11} thus displaced are now substituted for those deleted from winding B_{21} , in slots 61, 62, and 66. While the illustrated bridge windings are wound in a common direction, the interchanged windings carry horizontal deflection current which flow in opposing directions. When vertical deflection current is applied to the bridge windings, additive fluxes will be produced in the same manner as if the winding turns had never been interchanged. The effective vertical winding distribution thus remains unchanged.

For horizontal deflection current, however, fluxes are produced by each bridge winding which buck those produced about the interchanged turns such that the interchanged turns effectively cancel the adjacent, original bridge winding turns to produce a subtractive effect and thus nullify the horizontal deflection flux in portions of the region illustrated. The turns of winding B_{21} which extend into the second quadrant and are interspersed with those of winding B_{11} correspond to the second winding segment q of FIG. 10. Similarly, turns of winding B_{11} which extend into the first quadrant symmetrically with segment q of winding B_{21} correspond to segment p of FIG. 10.

In the example illustrated in FIG. 7, a total of 59 turns are provided in each of the vertical windings with 50 turns in each bridge winding. The horizontal windings each have a total of 64 turns therein. It will be understood that the inductance L_v presented to the vertical deflection drive system is then due to

$$2(59 + 50)$$

or

218 turns

while the inductance L_h presented to the horizontal system is attributable to

$$2(64 + 50)$$

or

228 turns

The resistance R_v of the overall vertical winding system is

$$2R(59 + 50/2) \text{ or } 168 \text{ R ohms}$$

while the horizontal resistance R_h is

$$2R(64 + 50/2) \text{ or } 178 \text{ R ohms.}$$

For the improved circuit of FIG. 7a, the inductance of the aggregate effective vertical turns is due to

$$2(53 + 56) = 218 \text{ turns}$$

while horizontal inductance is due to the presence of

$$2(64 + 53 - 3) = 228 \text{ turns.}$$

While the inductance of the horizontal and the vertical effective winding distribution is substantially the same, the presence of additional bridge-connected winding turns reduces the resistance of the overall vertical winding system to

$$2R(53 + 56/2)$$

or

$$162 \text{ R ohms}$$

while that of the horizontal system is now

$$2R(64 + 56/2)$$

or

$$184 \text{ R ohms.}$$

The illustrated modification in turns placement makes it possible to reduce the vertical deflection winding turns to a single layer so that the turns may be wound in a continuous, progressive manner without the need to "back up" to deposit a second layer of turns.

The effect of the modified turns placement shown in FIG. 7a may be seen in the plot of effective horizontal winding distribution of FIG. 8. For clarity the terminal portion of the curve is shown in expanded form. The dotted portion of the curve extending for the last 8° of the quadrant (here equivalent to six slots or turn positions) represents the effect of the additional bridge-connected winding turns. The percent of effective winding, measured from the center of the horizontal winding, decreases for slots 61-62, reflecting the presence of the turns interposed from bridge winding B_{11} . The percentage of total winding then increases for the following three slots due to the presence of the additional turns of bridge winding B_{21} in slots 63-65. The distribution then decreases by one slot due to the presence of the oppositely-directed current in the final turn of the quadrant. The three additional turns of bridge winding B_{21} have thus been nulled by the presence of the three counter-wound turns borrowed from winding B_{11} so that the total percentage of windings from center has not been affected. As described above, for the vertical effective winding distribution nine effective turns continue to be present in slots 61-66 such that there is no demonstrable change in the effective vertical winding distribution plotted in FIG. 9.

As will be evident from the foregoing description, certain aspects of the invention are not limited to the particular details of the examples illustrated, and it is therefore contemplated that other modifications or applications will occur to those skilled in the art. For instance, the number of turns in a given bridge winding is not necessarily an even number, and the grouping of interspersed ones of turns of adjacent bridge windings may be varied to suit a particular application. It is accordingly intended that the appended claims shall cover all such modifications and applications as do not depart from the true spirit and scope of the invention.

What is claimed as new and desired to be secured by Letters Patent of the United States is:

1. Means for effecting the periodic deflection of an electron beam within a cathode ray tube, comprising:

core means adapted to be disposed about the neck of the cathode ray tube;
a first pair of windings disposed on said core means for deflecting the electron beams in a first direction;
a second pair of windings disposed on said core means for deflecting the electron beam in a second direction substantially perpendicular to the first direction;
first, second, third, and fourth windings disposed on said core means and connected in series relationship with one another to form a closed loop, said first and said second windings each having at least

one turn disposed intermediate the ends of the other;
 said third and said fourth windings each having at least one turn disposed intermediate the ends of the other;
 means for coupling the junction of said first and said second, and the junction of said third and fourth, windings in series circuit relationship with said first pair of windings across a first source of deflection signals; and
 means for coupling the junction of said second and third, and the junction of said fourth and first, windings in series circuit relationship with said second pair of windings across a second source of deflection signals.

2. The invention defined in claim 1, wherein said turns disposed intermediate the ends of another winding are disposed upon the core means in such a manner that deflection signals from the second source produce magnetic flux which aids, and deflection signals from the first source produce magnetic flux which opposes, the flux produced by the winding intermediate whose ends said turns are disposed.

3. The invention defined in claim 1, wherein said first pair of windings is adapted to deflect the electron beams in a horizontal direction, and said second pair of windings is adapted to deflect the electron beams in a vertical direction.

4. In a color television receiver including a cathode ray tube having electron gun means adapted to produce a plurality of electron beams, means for periodically deflecting the electron beams, comprising:

annular core means adapted to be disposed about the neck of the cathode ray tube;
 a first pair of windings associated with said core means for deflecting the electron beams in a direction perpendicular to a given plane;
 a second pair of windings associated with said core means for deflecting the electron beams in a direction substantially parallel to said given plane;
 first, second, third, and fourth windings disposed on said core means connected in series relationship with one another to form a closed loop, each of said first, second, third, and fourth windings comprising a first and a second segment;
 the second segments of said first and second windings being disposed on said core means intermediate the first and second segments of the other;
 the second segments of said third and fourth windings being disposed on said core means intermediate the first and second segments of the other;
 means for coupling the junctions of said first and said second, and third and said fourth, windings in series circuit relationship with said first pair of windings across a first source of deflection signals; and

means for coupling the junctions of said second and third, and said fourth and first, windings in series circuit relationship with said second pair of windings across a second source of deflection signals.

5. The invention defined in claim 4, wherein said second segments of said windings are disposed on said core means in such a manner that deflection current from the second source of deflection signals produces magnetic fluxes about the second segments which aid, and deflection current from the first source of deflection signals produces magnetic fluxes about the second

segments which oppose, the fluxes produced by the winding intermediate whose segments they are disposed.

6. In a television receiver containing deflection apparatus for deflecting the electron beams of the cathode ray tube, said deflection apparatus including a core for receiving the neck portion of said cathode ray tube and horizontal and vertical windings wound on said core, wherein proper deflection of said electron beams requires sufficient windings such that adjacent horizontal and vertical windings are ordinarily caused to overlap, the improvement comprising:

first, second, third and fourth auxiliary windings wound on said core, each of said auxiliary windings having turns proportional to the number of overlapped turns between adjacent horizontal and vertical windings,

each auxiliary winding replacing the overlapped portion of each of adjacent horizontal and vertical windings such that shortened horizontal and vertical windings are utilized,
 said auxiliary windings being serially interconnected to form a closed loop,
 said shortened horizontal windings connecting selected alternate junctions of said auxiliary windings to a source of horizontal deflection signals, and said shortened vertical windings connecting the other junctions of said auxiliary windings to a source of vertical deflection signals.

7. The improved deflection apparatus recited in claim 6 wherein said horizontal and vertical windings each contain a pair of windings,

one of said shortened horizontal windings being connected to the junction between the first and second auxiliary windings, the other of said shortened horizontal windings being connected to the junction between said third and fourth auxiliary windings, one of said shortened vertical windings being connected to the junction between said second and third auxiliary windings, the other of said shortened vertical windings being connected to the junction between said fourth and first auxiliary windings.

8. In a television receiver deflection apparatus for deflecting the electron beams in the cathode ray tube comprising:

a core for receiving the neck portion of said cathode ray tube, horizontal windings, vertical windings and first, second, third and fourth auxiliary windings contiguously wound on said core,
 said first, second, third and fourth auxiliary windings being serially interconnected to form a closed loop,

said horizontal windings connecting the junctions between said first and second and third and fourth auxiliary windings to a source of horizontal deflection signals to form a series connection between said horizontal windings, the source of horizontal signals and said auxiliary windings,

said vertical windings connecting the junctions between said second and third and fourth and first auxiliary windings to a source of vertical deflection signals to form a series connection between said vertical windings, the source of vertical signals and said auxiliary windings.

9. The deflection apparatus recited in claim 8 wherein said horizontal windings comprise first and second windings,

the first horizontal winding connecting the junction between said first and second auxiliary windings to the source of horizontal signals, the second horizontal winding connecting the junction between said third and fourth auxiliary windings to the source of horizontal signals, and said vertical windings comprise first and second windings,

the first vertical winding connecting the junction between said second and third auxiliary windings to the source of vertical signals, the second vertical winding connecting the junction between said fourth and first auxiliary windings to the source of vertical signals.

10. The deflection apparatus as recited in claim 8 wherein said horizontal windings and said auxiliary windings comprise a first set of windings disposed about a first pair of diametrically opposite points on said core and being arranged about each of said points to provide an effective winding distribution substantially characterized by $\sin\phi + 0.08 \sin(3\phi)$ where ϕ represents the angular displacement from the geometric center of the winding,

and said vertical windings and said auxiliary windings comprise a second set of windings disposed about a second pair of diametrically opposite points on said core displaced substantially 90° from the first points and being arranged about each of said second points to provide an effective winding distribution substantially characterized by $\sin\phi - 0.06 \sin(3\phi)$.

11. The invention defined in claim 5 wherein said first pair of windings and said first, second, third and fourth windings comprise a first set of windings disposed about a first pair of diametrically opposite points on said core and being arranged about each of said points to provide an effective winding distribution of substantially sinusoidal form,

and said second pair of windings and said first, second, third and fourth windings comprise a second set of windings disposed about a second pair of diametrically opposite points on said core displaced substantially 90° from the first points and being arranged about each of said second points to provide an effective winding distribution substantially characterized by $\sin\phi + 0.04 \sin(3\phi) + 0.016 \sin(5\phi)$ where ϕ represents the angular displacement from the geometric center of the winding.
